Baltazar (45) **Date of Patent:** **** May 3, 2022**

(54) **TEMPERATURE THERAPY APPARATUS**(71) Applicant: **Biofreeze IP Holdings, LLC**, Akron, OH (US)(72) Inventor: **Carol Baltazar**, Glenwood, MD (US)(73) Assignee: **TheraPearl, LLC**, Columbia, MD (US)(***) Term: **15 Years**(21) Appl. No.: **29/740,215**(22) Filed: **Jul. 1, 2020****Related U.S. Application Data**

(60) Continuation-in-part of application No. 29/644,302, filed on Apr. 16, 2018, now Pat. No. Des. 904,632, which is a continuation-in-part of application No. 29/558,755, filed on Mar. 21, 2016, now abandoned, which is a continuation of application No. 29/498,785, filed on Aug. 7, 2014, now Pat. No. Des. 787,081, which is a continuation-in-part of application No. 29/429,154, filed on Aug. 7, 2012, now abandoned, which is a division of application No. 12/794,576, filed on Jun. 4, 2010, now abandoned.

(60) Provisional application No. 61/184,788, filed on Jun. 6, 2009.
